UNITED STATES PATENT OFFICE

THOMAS W. HOLT AND JOHN F. LEVAN, OF ELKHART, INDIANA, ASSIGNEES TO EXCEL CURTAIN COMPANY, OF ELKHART, INDIANA, A CORPORATION OF DELAWARE

CURTAIN-ROLLER CONSTRUCTION

Application filed February 8, 1929. Serial No. 333,557.

This invention relates to curtain rollers and the like and has for its object, a particularly simple and economical construction of a curtain roller and more especially the assembly 5 of the head of the barrel, the mandrel mounted therein to which the spring of the roller is attached and means for holding the head and the mandrel in assembled relation.

The invention consists in the novel features and in the combinations and constructions hereinafter set forth and claimed.

In describing this invention, reference is had to the accompanying drawing in which like characters designate corresponding parts 15 in all the views.

Figure 1 is an elevation, partly in section, of a roller embodying our invention.

Figure 2 is an enlarged fragmentary sectional view of the head and the mandrel and 20 contiguous parts.

Figure 3 is an end elevation of parts seen in Figure 2.

Figure 4 is a face view of one of the brackets for supporting the roller.

Figure 5 is an enlarged fragmentary detail 25 view illustrating the interlocking of the cross bar of the washer with the bifurcated end of the mandrel.

Figure 6 is an enlarged perspective view of 30 the head, mandrel and contiguous parts shown as separated.

This roller comprises generally, a barrel, heads at the ends of the barrel, a mandrel mounted in the barrel and extending through 35 one of the heads thereof, the part projecting beyond the heads forming an axle for the roller, this part being bifurcated providing separated tongues and means for securing the head to the axle to hold them from relative

40 axial movement, said means including a thrust member or washer having a diametrically extending bar for entering between the bifurcations and said bifurcations having means for interlocking with the cross bar and holding the thrust member or washer from axial movement, the annular part of the body of the thrust member or washer holding the bifurcated end from spreading under the torque action of the cross bar in the 45 use of the roller.

1 designates the barrel of the roller which may be of any suitable form, size and construction, it being here shown as rolled up from sheet metal into tubular form and also formed with a lengthwise groove 2 in which the curtain is secured or in which the means which is attached to the curtain is secured. The barrel construction forms no part of this invention. 55

3 and 4 designate the heads or flanges at opposite ends of the barrel. The heads are secured in the barrel in any suitable manner. As here illustrated, each head is formed with prongs 5 arranged to snugly fit within the barrel and these prongs may be secured to the barrel by indenting the barrel into the prongs or they may be frictionally held in position. The prongs extend on opposite sides of the walls of the groove 2 so that the walls of the groove serve as a key or spline 65 to key the heads to the barrel. These prongs are preferably struck up from a discoidal base 6 lying against the adjacent head and secured thereto in any suitable manner as by riveting. This feature forms no part of this invention. 70

The head 4 is formed with a central opening 7 for receiving a stud provided on the supporting bracket 8.

9 is a mandrel rolled up of sheet metal into 80 tubular form, the mandrel being arranged coaxially of the roller and projecting beyond the head 3 forming an axle for coaxing with a supporting bracket 10. The mandrel 9 at its inner end extends through an opening 11 85 in an internal bearing disk 12 fixed in the barrel and is journaled at its outer end in the head 3.

13 is a torque spring coiled about the mandrel and anchored at one end at 14 thereto 90 and at its other end to the prongs 5 which are secured to the head 3. Thus, the spring when tensioned, tends to turn the roller 1, assuming of course, that the mandrel is held from turning movement. The mandrel at its outer end is formed bifurcated by forming diametrically opposite lengthwise slots 9^a therein. As the mandrel is formed of resilient sheet metal, these slots provide resilient spring tongues. 95

The means for holding the head 3 and hence, the barrel from axial movement on the mandrel or the barrel and the mandrel from relative axial movement, comprises one or more thrust members 15, 18. As here shown, there are two thrust members, one located on the inner and the other on the outer side of the head 3. The member 15 is a thrust washer fitting on the mandrel and having a cross bar 17 extending through the slots 9^a of the mandrel, that is, between the bifurcations at the end of the mandrel, the cross bar abutting against the bottoms or inner ends of the slots. The thrust washer 15 overlies the discoidal body 6 on which the prongs 5 are provided and usually an ordinary fiber washer 15^a is interposed between the member 15 and the discoidal body 6.

The member for holding the head 3 and mandrel 4 from relative axial movement outwardly, comprises a washer 18 having a diametrically extending cross bar 19 extending between the bifurcations at the end of the mandrel, the bifurcations being formed with means for interlocking with the cross bar 19 with a snap action, this means being here shown as ratchet teeth 20 projecting into the slots 9^a in order to engage behind the cross bar 18 when it has reached its final assembled position.

Preferably, the inner portion of the slots between the bifurcations are wider than between the outer or entrance portions and the cross bar 19 is of greater width than the outer portions of the slots providing the ratchet teeth 20, so when the washers are placed in position, particularly the outer washer 18, the bar 19 will tend to spread somewhat, the resilient bifurcations and hence, when the cross bar reaches its final position in the wider portions of the slots, the spring arms will react causing the teeth 20 to ratchet or snap into engagement with the cross bar and hold the member 18 from outward displacement. The annular part of the washer holds the bifurcations or prongs from distorting due to torque applied by the crossbar to the rotating roller during the winding and unwinding thereof.

The member 18 is formed with peripheral ratchet teeth 21 for coacting with pawls 22 on the head of the roller in the usual manner. The bifurcated outer end of the mandrel also enters a socket 23 in the supporting bracket 10 and moves astride a cross bar 24 in said socket. The inner end of the mandrel is similarly bifurcated at 25 and has a washer 26 thereon having its cross-bar similarly interlocked with the bifurcated inner end. This washer 26 coacts with the disk 12. The disk 12 and mandrel are assembled as a unit and hence, are removable and replaceable in the barrel as a unit through one end of the barrel.

Owing to the resilient bifurcations and the projections or ratchet teeth thereon and the

cross bars of the washers 15 and 18, the washers are assembled in a particularly simple and economical manner and owing to the fact that the mandrel is formed hollow or rolled up from a strip of sheet metal, the resilient bifurcations are economically provided.

What we claim is:

1. A curtain roller construction comprising a barrel, heads at the ends of the barrel, a hollow mandrel mounted in the barrel and extending through one of the heads thereof, the part projecting beyond the head forming an axle for the roller, a torque spring encircling the mandrel and anchored at one end to the barrel and at its other end to the mandrel, the end of the mandrel which projects through the head being formed of resilient material and with a lengthwise slot forming the axle end of the mandrel bifurcated, the slot providing the mandrel with resilient tongues on opposite sides of the slot, a thrust member mounted on the bifurcated end adjacent the head and having a diametrically extending cross bar for entering the slots of the axle and thrusting against the bottom of the slot, said thrust member being located on the inner side of the head, a second thrust member mounted on the axle outside of the head and having a diametrically extending cross bar located in said slot, the cross bar of the second member and the walls of the slot having means for interlocking with a snap action to hold the second member from endwise movement when it is in its final position.

2. A curtain roller construction comprising a barrel, heads at the ends of the barrel, a hollow mandrel mounted in the barrel and extending through one of the heads thereof, the part projecting beyond the head forming an axle for the roller and said part being formed of resilient material and bifurcated forming spring tongues and a bracket formed with a socket for receiving the axle and a diametrically extending cross bar for entering between the spring tongues.

3. A curtain roller construction comprising a barrel, heads at the ends of the barrel, a mandrel mounted in the barrel, and extending through one of the heads, the part projecting beyond the head forming an axle and being formed of resilient material and bifurcated forming spring tongues and means for holding the mandrel from axial movement relatively to the head comprising a thrust member mounted on the bifurcated axle and having a diametrically extending cross bar for entering between the bifurcations, the bifurcations being formed with ratchet teeth for engaging the cross bar and holding the thrust member from endwise movement.

4. A curtain roller construction comprising a barrel, heads at the ends of the barrel, a mandrel mounted in the barrel and extend-

- ing through one of the heads thereof, the part projecting beyond the head forming an axle for the roller and being formed of resilient material and bifurcated thereby providing 5 spring tongues, means fitting on the mandrel thrusting against the inner and outer faces of the head in which the axle is mounted, said means comprising washers fitting the mandrel and having diametrically extending cross bars for entering between the bifurcations, said bifurcations being formed with ratchet teeth for coacting with the cross bar of the outermost washer and holding it from axial movement outwardly.
- 10 5. A curtain roller construction comprising a barrel, heads at the ends of the barrel, a hollow sheet metal mandrel mounted in the barrel and extending through one of the heads thereof, the part projecting beyond the head forming an axle for the roller, said axle being formed of resilient material and bifurcated thereby providing opposing spring tongues and means for holding the mandrel from axial movement relatively to the head,
- 20 25 said means comprising a washer fitting the periphery of the mandrel and having a cross bar extending between the bifurcations.
6. A curtain roller construction comprising a barrel, heads at the ends of the barrel, a hollow mandrel mounted in the barrel and extending through one of the heads thereof, the part projecting beyond the head forming an axle for the roller, said axle being formed of resilient material and bifurcated, thereby 30 providing opposing spring tongues and means for holding the mandrel from axial movement relatively to the head, said means having a portion extending between the bifurcations, said means and the bifurcations 35 having means for interlocking with a ratchet action when said means is placed in final position on the mandrel and thereby preventing relative axial movement of the mandrel and the head.
- 40 45 7. A curtain roller construction comprising a barrel, a bearing member in the barrel, a head at one end of the barrel, a hollow tubular mandrel mounted in said bearing member and the head and having its ends bifurcated, the bifurcations being of resilient metal thereby providing spring tongues, means for holding the mandrel from axial displacement comprising washers fitting the bifurcated ends and each having a cross-bar 50 55 extending between the bifurcations at each end.
8. A mandrel for curtain rollers and the like, said mandrel being tubular and slotted at one end to form a bifurcated end, said end being formed of resilient metal, a thrust member comprising a washer fitting the mandrel and having a cross bar extending through the slotted end.
- 60 65 9. A mandrel for curtain rollers and the like, said mandrel being tubular and slotted
- at one end to form a bifurcated end, said end being formed of resilient metal, a thrust member comprising a washer fitting the mandrel and having a cross bar extending through the slotted end, the cross bar and the bifurcations at said end having means for interlocking.
- 70 10. A curtain roller construction comprising a barrel, heads at the ends of the barrel, a hollow tubular mandrel formed in a strip of sheet metal rolled in tubular form, a portion of the mandrel extending beyond one of the heads forming the axle for the roller, a torque spring located in the barrel and connecting the barrel and the mandrel, the axle being bifurcated at one end, said end being formed of resilient metal, thereby providing two tongues and means for holding the mandrel from axial movement comprising a washer abutting against the head and having a cross bar extending between the tongues.
- 75 80 11. A curtain roller construction comprising a barrel, heads at the ends of the barrel, a hollow tubular mandrel formed in a strip of sheet metal rolled in tubular form, a portion of the mandrel extending beyond one of the heads forming the axle for the roller, a torque spring located in the barrel and connecting the barrel and the mandrel, the axle being bifurcated at one end, said end being formed of resilient metal, thereby providing two tongues and means for holding the mandrel from axial movement comprising a washer abutting against the head and having a cross bar extending between the tongues,
- 85 90 95 100 105 110 115 120 125 130
12. A curtain roller construction comprising a barrel, heads at the ends of the barrel, a hollow resilient sheet metal mandrel mounted in the barrel and extending through one of the heads thereof, the part projecting beyond the head forming an axle for the roller, said axle having lengthwise slots at its ends bifurcating the axle, the projection part being formed of resilient metal, whereby the bifurcations provide spring tongues, a thrust member for holding the head and mandrel from relative axial movement comprising a washer having a cross bar extending transversely through the slots, the slots being wider toward their inner ends than their outer ends providing ratchet teeth and the cross bar being wider than the narrow portions of the slots.
- In testimony whereof, we have hereunto signed our names, at Syracuse, in the county of Onondaga, and in the State of New York, this 28th day of January, 1929.
